UNITED STATES PATENT OFFICE.

DENIS O'CONNOR, OF JOLIET, ILLINOIS, ASSIGNOR OF FIVE-SIXTHS TO ARTHUR M. SCHUSTER AND JOHN P. SCHUSTER, OF JOLIET, ILLINOIS.

WRENCH.

1,288,969.

Specification of Letters Patent. Patented Dec. 24, 1918.

Application filed January 7, 1916. Serial No. 70,711.

To all whom it may concern:

Be it known that I, DENIS O'CONNOR, a subject of Great Britain, and resident of Joliet, Will county, Illinois, have invented 5 a certain new and useful Improvement in Wrenches, of which the following is a specification.

My invention has for its principal object to provide a movable jaw with manually 10 operable adjusting means whereby it may be set at any point within the limits of the capacity of the wrench, and combine therewith an automatically operated adjusting means whereby the jaw is capable of considerable 15 movement beyond its manually adjusted position, whereby the wrench is made capable of use on two or three sizes of pipe without readjustment of the manually operable nut.

With this object in view, my invention 20 consists in certain novel features of construction hereinafter described and shown in the accompanying drawings, in which Figure 1, is a side view, in perspective, with 25 parts broken away, showing my improved construction. Fig. 2, is a perspective view of the movable jaw. Fig. 3, is a perspective view of the fixed jaw. Fig. 4, is a bottom view, in perspective, of a flanged bearing 30 member. Fig. 5, is a perspective view of the hollow body portion and handle of my improved wrench.

In the drawings, in which similar reference characters refer to similar parts 35 throughout the several views, I have illustrated the preferred embodiment of my invention and show same as consisting of the main body portion 6, the fixed jaw 7, the pivoted or movable jaw 8, the adjusting 40 nut 9, and the flanged pivot bearings 10.

The body portion 6, is provided with the handle 11, and may be made in the form of a hollow steel or malleable casting as shown in Fig. 1, or may be forged from plate steel 45 as shown in Fig. 5. The fixed jaw 7, is removably secured to the upper end of the body portion by the screws 12, which may be made to pass loosely through one wall of the body portion and through the openings 7^a in the shank 7^b of the jaw and screw threaded into the opposite wall of the body. The upper edge of the body walls may, as shown in Fig. 1, be recessed as at 50 6^a to receive the flanges 7^c of the jaw, forming a means of further securing or anchoring the jaw in place.

The movable jaw 8, is provided with the shank 13, extending at a right angle to the serrated face 14, and is passed through the opening 15, which opening is bounded by 60 the upper edge of the walls and the rear rounded portion 7^d of the jaw 7. The shank is pivotally secured to the interior of the body and is capable of a rotating or oscillating movement about its pivotal connection to an extent as defined by the length of the opening 15.

The method of pivotally connecting the movable jaw within the body, I consider one of the most important features of my improved wrench. This consists in providing the body 6, with the openings 16, which with the peripheral slots 17, are in register with each other. Fitted in these openings are the flanged pivot bearing members 10, one 75 on each side of the body with the hub portion 18, entering and snugly engaging the opening and the flanges over-lapping the sides of the body. These bearings are held in position by the screws 19, which pass 80 loosely through the flanges of one bearing and through the slots 17, and are screw threaded into the flange of the other bearing. They are not clamped against movement relative to the body, but are free to 85 rotate or oscillate to an extent as limited by the slots 17.

Loosely caged between the bearings 10, is the knurled cylindrical or barrel-shaped adjusting nut 2, with its sides exposed through 90 the openings 20, in the bearings whereby it may be manually revolved in either direction. The edges of the opening adjacent the periphery of the nut are beveled, approximating the contour of the cylindrical 95 surface of the nut, while the edges of these openings adjacent the ends of the nut are square, affording a solid, unyielding surface to resist the thrust of the nut when the wrench is in heavy duty. It will be observed that these end walls of the openings have a width equal to the thickness of the flange and the hub portions 18, as shown at 100 21. The adjusting nut is threaded to engage the threaded surfaces 22, of the shank 13, whereby the jaws can be adjusted to the 105 limits of the wrench's capacity.

From the foregoing it will be seen that the movable jaw is free to oscillate a distance as limited by the length of the opening 15, 110 and that the flanged bearing members 10, rotate with the shank of the jaw and the ad-

justing nut 9, on the hub portions 18, which extend into the openings 16, in the body of the wrench. These flanged bearings not only provide a large, liberal pivot, insuring 5 against wear occasioned by the frequent oscillation of the jaw shank, but what is of greater importance, they form a substantial and practically indestructible means of resisting the pulling strains transmitted by 10 the adjusting nut 9, when the wrench is subjected to heavy duty. The ends of the barrel-shaped nut being square and in direct contact with the square end of the openings 20, the thrust or strain from the jaw shank 15 is transmitted directly to the hub portion of the bearings 10, and by them to the body of the wrench. When ball or spherical shaped adjusting nuts are used the pulling strains of the shank tend to wedge the ball between 20 the walls of the body, spreading them to their final destruction, but by the use of the barrel-shaped nut the strains are resisted without the least liability of injury to the body. 25 When in normal position, the serrated faces of the jaws are parallel and the shank 13, is at an angle to the wrench handle, and with the jaws adjusted by manipulating the nut 9, to properly grasp a pipe, a further automatic adjustment of considerable extent is 30 possible through the oscillations of the movable jaw on its pivot. This automatic adjustment is of importance in that the wrench is capable of use on two or three sizes of 35 pipe or will grasp a pipe and its attached fittings without readjustment of the nut.

To positively return the movable jaw 8, to normal position after having been oscillated on its pivot, I provide the spring 25, one 40 end of which is coiled about the post 26 affixed to one of the walls of the hollow body, while the other end, which is provided with the roller 27, bears against the rear of the shank with the roller engaging the groove 45 28, milled through the threaded surface 22. The roller 27 is secured to the spring by having the end of the spring extend through the hub of the roller. Causing the spring to bear against the shank above its pivotal 50 connection with the body, its efficiency is unimpaired regardless of the relative position of the end of the shank and the adjusting nut.

It will be observed that the two rotatable 55 disks 10 together with the connecting pins 13 form virtually a unitary structure, since the pins cause the disks to rotate together. In this way, it will be observed that a broad, substantial and durable bearing for the nut 60 is provided.

What I claim as new is,

1. In a wrench, a handle, a hollow body

portion having circular holes whose edges are notched, a movable jaw provided with a shank arranged lengthwise within said body portion, a substantially barrel-shaped adjusting member having a threaded opening longitudinally thereof to receive the shank of said movable jaw adapted to adjust said jaw to and from said body portion, oppositely disposed bearing-members mounted for a limited rotative movement in said circular holes, said bearing members having openings adapted to expose the sides of said adjusting member for manual engagement, 75 and pins extending through the hollow body portion and connecting said bearing-members, these pins being in engagement with said notches, for the purpose set forth.

2. In a wrench of the class set forth, a hollow body having a handle at one end and a stationary jaw at the other end, this latter end being provided with an opening in its end wall and the walls of the body being provided with coincident circular holes, a 85 movable jaw having a threaded shank extending into said opening in the end wall of the body, a manually operable nut on said shank, and a bearing for said nut consisting of a pair of disks rotatably fitting in said 90 circular holes in the body walls, said disks having annular flanges fitting against the outer face of the hollow body, and means extending through the body to connect said disks to cause them to rotate together as a 95 single structure.

3. In a wrench, a hollow body portion, a jaw removably fixed to the upper end of said body portion, a movable jaw normally in parallelism with said fixed jaw provided with a shank arranged lengthwise within said body portion, a barrel-shaped adjusting member having a threaded opening longitudinally thereof to receive said shank adapted to adjust said jaw to and from said body portion, coinciding openings in the sides of said body portion, flanged bearing members provided with hub portions mounted in said openings for a limited oscillating movement, adapted to rotatively support said adjusting member, whereby said movable jaw may move considerably out of parallelism with said fixed jaw, a spring secured to said body portion provided with a roller at its free end adapted to bear against the rear side of said shank at a point between its pivotal connection with the body and the movable jaw, whereby the jaws are maintained in and returned to their normal position at any point of adjustment of the movable jaw relative to the body portion.

Signed by me at Joliet, Illinois.

DENIS O'CONNOR.
